UNITED STATES PATENT OFFICE

2,053,825

ROCK DUSTER

Albert J. Gurney, Canton, Ohio, assignor to The
American Mine Door Company, Canton, Ohio,
a corporation of Ohio

Application May 16, 1934, Serial No. 725,887

9 Claims. (Cl. 302—50)

The invention relates to apparatus for spraying rock dust or the like upon the ceilings, walls and floors of coal mines, in order to cover or mix with the coal dust ordinarily deposited in such places, for the purpose of preventing explosions of the coal dust, and more particularly to a simple and inexpensive rock duster especially adapted for use in smaller mines.

It is common practice to spray the interiors of mine tunnels with rock dust, and apparatus, such as shown in my prior Patent No. 1,852,649, is commonly used for this purpose in large mines, but since it is only necessary to spray with rock dust about twice a year, the cost of such large apparatus makes the use of the same prohibitive to the small mine operator.

Therefore, an object of the present improvement is the provision of a small and inexpensive rock duster which is adapted for use in small coal mines, and which has sufficient capacity to carry the rock dust to every part of a small mine.

Another object of the improvement is to provide a new and novel form of mixing nozzle for mixing the air blast and rock dust and discharging the mixture through a hose or the like.

A further object is to provide a novel form of gear reduction for operating the working parts of the rock duster.

A still further object is to provide a hopper for containing the rock dust so shaped that the motor and blower are protected thereby from dust.

The above objects, together with others which will be apparent from the accompanying drawings and following description, or which may be later pointed out, may be attained by constructing the improved rock duster in the manner illustrated in the accompanying drawings, in which

Figure 1 is a top plan view of the improved rock duster, with parts broken away for the purpose of illustration;

Fig. 2, a rear end elevation of the apparatus with portions broken away;

Fig. 3, an enlarged longitudinal section through the improved mixing nozzle which mixes the air blast and rock dust and discharges the mixture through a hose or the like;

Fig. 4, an elevation of the improved gear reduction;

Fig. 5, a transverse section through the gear reduction taken as on the line 5—5, Fig. 4; and

Fig. 6, a section as on the line 6—6, Fig. 4.

Similar numerals refer to similar parts throughout the drawings.

The improved apparatus is designed to be moved through a mine upon rails, and for this

purpose may include the frame 10, provided with axles 11 having flanged wheels 12 arranged to run upon the rails 13.

The hopper 14 is mounted upon the frame, for the purpose of containing a supply of rock dust, 5 this hopper preferably being of substantially V-shape, as best shown in Fig. 2, and having the overhanging, horizontal shelves 15 at its upper end, terminating in the depending, strengthening flanges 16. An end plate 17 may be attached to 10 each end of the hopper to close the ends thereof and to strengthen and support the shelves 15.

The motor 18, which operates the working parts of the apparatus, may be located upon the frame adjacent to one side of the V-shape hopper 14 15 and beneath the adjacent shelf 15 so that it is protected from rock dust spilling upon the same from the trough and the blower 19 may be housed in the same manner upon the other side of the hopper and beneath the other shelf 15 so that 20 both of these parts are protected by the trough and shelves thereon.

A gear housing 20 is located at the rear end of the hopper 14 to enclose the drive and reduction gear from the motor to the blower and conveyer 25 screw 21 respectively. The shaft 22 of the motor may have a sprocket wheel 23 fixed thereon, within the gear housing 20, a chain 24 passing over said sprocket wheel and over a similar sprocket wheel 25 fixed upon the shaft 26 of the blower 19 30 whereby the blower is driven directly from the motor.

For the purpose of driving the conveyer screw 21 at the desired speed, a novel reduction gear 35 is provided which may be driven by a pinion 27 fixed upon the motor shaft 22 and meshing with a gear 28 keyed to the hub of an eccentric 29. The eccentric 29 is journaled upon a shaft 30 secured within the gear housing, and is surrounded by the eccentric band 31 which may be provided with an annular groove to receive the split spring ring 32, the angular ends 33 of which may be received in a cut-out portion of the groove indicated at 34. When this split spring ring is sprung into place as shown in Fig. 4, the eccentric band 31 will be retained upon the eccentric 29.

A ratchet gear 35 is fixed upon the shaft 36 of the conveyer screw 21 as by the keys 37. A rigid arm 38 is carried by the eccentric band 31 and is pivotally connected at its end, as by the stud 39, to the outer rocker arm 40 having the angular free end 41. A journal portion 42 is formed upon the inner end of the rocker arm 40 and is journaled upon the journal portion 43 of the inner rocker arm 44.

A pawl 45 is pivoted upon the stud 39 and a spring 46 is provided for normally urging said pawl into engagement with the teeth of the ratchet gear 35. An arm 47 is pivoted as at 48 5 upon the eccentric band 31, the other end thereof being pivotally connected to the inner rocker arm 44 as by the stud 49 upon which is pivoted the pawl 50, similar to the pawl 45 and arranged to be normally urged into contact with the teeth 10 of the ratchet gear 35 as by the spring 51.

Each of the pawls 45 and 50 is provided with a curved lug 52 adapted to ride over the arcuate surfaces 53 of the pawl release 54 which is provided with a journal portion 55 journaled upon 15 the bushing 56 surrounding the reduced portion 57 of the conveyer screw shaft 36 and also journaled within the bearing boss 53 formed upon the gear housing 20. A thrust ball 59 may be provided within the recess 60 of the journal portion 55 bearing against the reduced end 57 of the shaft 36, which shaft may be journaled through a bushing 61 provided in the bearing boss 62 formed in the housing 20.

A handle lever 63 is fixed to the journal portion 55 of the pawl release as by the collar 64 formed upon the handle and the pin 65 passed through said collar and through the journal portion 55. This handle is adapted to be moved across the control segment 66 fixed upon the rear side of 30 the housing 20 and having apertures 67 adapted to be selectively engaged by a pin 68 upon the handle knob 69 for holding the pawl release in off position or in position for feeding sufficient rock dust to the feed jet to accommodate a 35 hundred foot hose or fifty foot hose, as indicated on Fig. 2 of the drawings.

It will be seen that as the handle is rotated to the off position, the arcuate surfaces 53 of the pawl release will be so positioned that through 40 the entire stroke of the pawls 45 and 50, the curved lugs 52 of the pawls will ride upon the arcuate surfaces 53 of the pawl release so that the ratchet gear 35, and with it the conveyer screw, will not be rotated. Regardless of the position 45 of the pawl release 54, the blower will continue to operate directly from the motor during all times that the motor is in operation.

The conveyer screw 21 is located in a substantially half-round groove or trough 70 in the bottom 50 of the V-shaped hopper 14 and the forward end portion thereof may be enclosed by the substantially half-round plate 71, said forward end of the conveyer screw passing through the opening 72 in the forward end wall of the hopper and 55 extending into the inner feed tube 73 of the mixing nozzle, the end of the shaft being reduced as at 74 and journaled in the bushing 75 within the bearing member 76 which may be centrally supported in spaced relation within the feed tube 73 as by the ribs 77, a semi-elliptic nose 78 being formed upon said bearing member.

The forward end of the inner or rock dust feed tube 73 is tapered as shown at 79, the taper being considerably less than the taper of the nose 65 78 or the tapered forward end portion 80 of the outer or air feed tube 81. This tapered forward end portion 80 of the outer feed tube terminates beyond the tapered end 79 of the inner feed tube at a distance substantially one-half the diameter 70 of the inner feed tube. This outer or air feed tube may be provided at its rear end with the angular flange 82 having the central opening 83 adapted to fit upon the shoulder 84 of the inner or rock dust feed tube 73. The flange 82 75 is also adapted to fit against a similar flange 85

upon the inner feed tube which fits against the adjacent end wall of the hopper 14, the flanges being adapted to be connected thereto in any usual and well known manner.

An outwardly tapered inlet neck 86 is provided 5 upon the outer or air feed tube 81 provided at its end with a flange 87 adapted to be connected to a similar flange 88 upon the air pipe 89 leading from the blower 19. The discharge end of the feed tube 81, beyond the tapered portion 80, may 10 be flared slightly outward as at 91, terminating in a flange 92 to which a hose coupling 93 may be attached as by bolts 94 for the purpose of securing a hose thereto.

In the operation of the improved rock duster, 15 the same may be moved over the usual rails 13 in the mine by means of a locomotive or the like and the rock dust from the hopper 14 is conveyed by the conveyer screw 21 into the inner or rock dust feed tube 73 and as it is pushed forward into the 20 tapered end portion 79 thereof, the rock dust may expand in the space between said tapered discharge end of the feed tube 73 and the tapered nose 78 and is picked up by the air blast passing through the outer or air feed tube 81, the mixture 25 being carried through the tapered portion 80 of the outer feed tube and then slightly expanded as it passes through the flared portion 91 thereof and is carried to the hose, by means of which it may be sprayed upon the ceilings, walls and floor 30 of the mine tunnel.

Where a short hose is connected to the mixing nozzle, the air creates a vacuum beyond the restricted end 79 of the inner or rock dust feed tube, drawing the dust out into the air stream. Where 35 a long hose is connected to the nozzle, the resistance of the air caused by friction forces a dust plug back into the end of the rock dust feed tube 73, preventing back pressure of air from forcing rock dust back into the hopper. Without means 40 for forming this dust plug, most of the air would pass back through the feed tube 73 into the hopper.

The handle lever 63 may be operated across the control segment 66 to adjust the gear reduction, 45 shown in Fig. 4, so as to provide the proper rate of feed of rock dust for either fifty foot or one hundred foot hose or so as to entirely cut off the supply of rock dust when desired.

I claim:

1. A rock duster including a mixing nozzle comprising an outer feed tube, means for admitting air to the rear portion thereof, an inner feed tube within the outer feed tube and spaced therefrom, the forward end of the inner feed tube 55 being tapered and terminating short of the outer feed tube, the forward end portion of the outer feed tube being tapered more than the inner feed tube, and terminating beyond the end of the inner feed tube at a distance substantially one-half the diameter of the inner feed tube, means for feeding rock dust and the like into the rear end of the inner feed tube, and means for connecting a hose to the forward end of the outer feed tube.

2. A rock duster including a mixing nozzle comprising an outer feed tube, means for admitting air to the rear portion thereof, an inner feed tube within the outer feed tube and spaced therefrom, the forward end of the inner feed tube being 70 tapered and terminating short of the outer feed tube, the forward end portion of the outer feed tube being tapered more than the inner feed tube and terminating beyond the end of the inner feed tube at a distance substantially one-half the 75

diameter of the inner feed tube and then outwardly flared, means for feeding rock dust and the like into the rear end of the inner feed tube, and means for connecting a hose to the forward 5 end of the outer feed tube.

3. A rock duster including a mixing nozzle comprising an outer feed tube, means for admitting air to the rear portion thereof, an inner feed tube within the outer feed tube and spaced therefrom, 10 the forward end of the inner feed tube being tapered and terminating short of the outer feed tube, a central obstruction of uniform diameter within the inner feed tube having a forwardly disposed tapered nose, means for feeding rock 15 dust and the like into the rear end of the inner feed tube, and means for connecting a hose to the forward end of the outer feed tube.

4. A rock duster including a mixing nozzle comprising an outer feed tube, means for admitting 20 air to the rear portion thereof, an inner feed tube within the outer feed tube and spaced therefrom, the forward end of the inner feed tube being tapered and terminating short of the outer feed tube, a central obstruction of uniform diameter 25 within the inner feed tube having a forwardly disposed nose tapered more than the inner feed tube, means for feeding rock dust and the like into the rear end of the inner feed tube, and means for connecting a hose to the forward end 30 of the outer feed tube.

5. A rock duster including a mixing nozzle comprising an outer feed tube, means for admitting air to the rear portion thereof, an inner feed tube within the outer feed tube and spaced therefrom, 35 the forward end of the inner feed tube being tapered and terminating short of the outer feed tube, the forward end portion of the outer feed tube being tapered more than the inner feed tube, a central obstruction of uniform diameter within 40 the inner feed tube having a forwardly disposed tapered nose, means for feeding rock dust and the like into the rear end of the inner feed tube, and means for connecting a hose to the forward end of the outer feed tube.

45 6. A rock duster including a mixing nozzle comprising an outer feed tube, means for admitting air to the rear portion thereof, an inner feed tube within the outer feed tube and spaced therefrom, the forward end of the inner feed tube being tapered and terminating short of the outer feed tube,

the forward end portion of the outer feed tube being tapered more than the inner feed tube, a central obstruction of uniform diameter within the inner feed tube having a forwardly disposed nose tapered more than the inner feed tube, 5 means for feeding rock dust and the like into the rear end of the inner feed tube, and means for connecting a hose to the forward end of the outer feed tube.

7. A rock duster including a mixing nozzle comprising an outer feed tube, means for admitting air to the rear portion thereof, an inner feed tube within the outer feed tube and spaced therefrom, the forward end of the inner feed tube being tapered and terminating short of the outer feed 15 tube, a feed screw for feeding rock dust and the like into the rear end of the inner feed tube, a bearing for said feed screw within the inner feed tube having a forwardly tapered nose, and means for connecting a hose to the forward end of the 20 outer feed tube.

8. A rock duster including a mixing nozzle comprising an outer feed tube, means for admitting air to the rear portion thereof, an inner feed tube within the outer feed tube and spaced therefrom, 25 the forward end of the inner feed tube being tapered and terminating short of the outer feed tube, a feed screw for feeding rock dust and the like into the rear end of the inner feed tube, a bearing for said feed screw within the inner feed 30 tube having a forwardly disposed nose tapered more than the inner feed tube, and means for connecting a hose to the forward end of the outer feed tube.

9. A rock duster including mixing nozzle comprising an outer feed tube, means for admitting air to the rear portion thereof, an inner feed tube within the outer feed tube and spaced therefrom, the forward end of the inner feed tube being tapered and terminating short of the outer 35 feed tube, the forward end portion of the outer feed tube being tapered more than the inner feed tube, a feed screw for feeding rock dust and the like into the rear end of the inner feed tube, a bearing for said feed screw within the inner feed 40 tube having a forwardly tapered nose, and means for connecting a hose to the forward end of the outer feed tube.

ALBERT J. GURNEY. 50
